UNITED STATES PATENT OFFICE

VICTOR W. HOYE, OF NEW CASTLE, PENNSYLVANIA

DRAFT REGULATOR FOR AUTOMOBILE RADIATORS

Application filed April 23, 1928. Serial No. 272,290.

This invention relates to improvements in draft regulators for controlling the evaporated liquids in automobile radiators.

One object of the invention is to provide a device of this character which will automatically seal the overflow pipe under all normal running conditions to prevent the escape of water or other fluids or vapors, but which will automatically vent the radiator when over-
10 heating and expansion of the liquids therein occurs.

Another object is to provide a draft regulator of this character which under normal running conditions will prevent objectionable
15 odors such as alcohol fumes, steam and the like from escaping and entering the automobile.

A further object is to provide a draft regulator which automatically seals the radiator
20 overflow pipe against draft caused by air rushing past the lower end of the pipe when the automobile is in motion and which action of the air creates a suction or draft through the pipe to the interior of the radiator.

Still another object is to provide a device of this character which will prevent the loss of liquids through the overflow pipe when the radiator is being filled.

30 With the foregoing and other objects in view the invention consists in the novel subject matter hereinafter described and claimed, the description being supplemented by the accompanying drawing.

35 Figure 1 is a rear elevation of the upper portion of an automobile radiator with parts broken away and in section, showing the application of one form of the invention.

Fig. 2 is a vertical sectional view of the form of the device illustrated in Fig. 1 showing in dotted lines the open position of the valve.

Fig. 3 is a perspective view of the same with the cap removed.

40 Fig. 4 is a side elevation partly in section of a modified form of the device.

The improved draft regulator and pressure relief valve is adapted for disposition at the upper end of the conventional radiator overflow pipe 6, which end is usually disposed in

the filling neck N of the radiator R. In Figs. 1 to 3 of the drawing, the device is shown as embodying a casing side wall 7, the upper portion of which is rectangular for reception within the flange of a rectangular flanged cover 8. The lower portion of the wall 7 is formed by a comparatively long tube 9 and a relatively short tube 10 disposed side by side and joined by a common vertical wall 11. This wall 11 terminates below the cover 8, leaving a communicating passage 12 between the upper ends of the tubes as shown in Fig. 2.

The lower end of tube 9 is enlarged to fit onto the upper end of the overflow pipe 6, the enlargement providing an annular stop shoulder 13 with which the upper end of the overflow pipe engages and which limits the downward movement of the tube on the pipe.

The other tube 10 has its lower end bent inwardly throughout its circumference to form a valve seat 14 with which is engaged a ball valve 15. The valve 15 normally closes the lower end of the tube 10 and prevents the escape of liquids, vapors or fumes from the radiator. When, however, undue expansion of the liquid in the radiator occurs from any cause, the pressure therefrom will lift the ball valve from its seat thus venting the radiator and relieving the pressure after which the ball will again drop onto its seat by gravity, thus automatically closing the tube and preventing any further escape of fumes, vapors or liquids from the radiator.

The form of the invention described in the foregoing is adapted for use in connection with overflow pipes already installed in radiators. The modified form of the invention shown in Fig. 4 of the drawing is used in connection with overflow pipes to be installed in radiators when they are built, and forms an integral part of the overflow pipe.

The modified construction of Fig. 4 embodies portions 9', 10' and 14' identical with corresponding parts above described, with the exception that the tube 9' is formed by a continuation of the upper end of the overflow pipe 6.

From the foregoing the operation of the device will be readily understood and it will

be seen that under normal running conditions, the use of my regulator will shut off draft and suction through the over-flow pipe thus preventing the escape of fumes, vapors and liquids from the radiator. It will also be seen that by the use of this invention on the upper end of the overflow pipe, the loss of liquid through the pipe when filling the radiator is prevented. The vapors retained in the radiator by the operation of my improved draft regulator will condense and return to their original form thus further eliminating waste.

I claim:

15 In a device of the class described, a casing side wall of rectangular form at its upper end and having its lower portion formed by a relatively short and a comparatively long vertical tube disposed side by side and joined 20 by a common vertical wall, said common vertical wall terminating below the upper end of said casing side wall leaving the two tubes in communication with each other at their upper ends, the lower end of said relatively short tube being bent inwardly 25 throughout its circumference to provide a valve seat, a ball valve in said relatively short tube resting on said seat, and a rectangular cover having a continuous flange surrounding and secured to said rectangular upper end of said casing side wall.

In testimony whereof I have hereunto affixed my signature.

VICTOR W. HOYE.
